DRAG ELIMINATOR FOR SHIPS

Filed Aug. 20, 1929

FIG.1.

FIG.2.

FIG.3.

FIG.4.

Inventor

Samuel Aitken

By his Attorney

Cooper, Kerr + Dunham

UNITED STATES PATENT OFFICE

SAMUEL AITKEN, OF EAST ORANGE, NEW JERSEY, ASSIGNOR TO DRAG ELIMINATOR COMPANY, INC., OF NEW YORK, N. Y., A CORPORATION OF DELAWARE

DRAG ELIMINATOR FOR SHIPS

Application filed August 20, 1929. Serial No. 387,229.

This invention covers improvements in boats or ships for the purpose of eliminating "drag" and thereby decreasing the power required for obtaining any desired speed, or 5 for increasing speed without increasing power.

The invention pertains especially to those portions of the ship which are below water level at the stern in the neighborhood of the 10 propeller.

It has been customary to leave broad comparatively flat surfaces across the stern frame and across the rear of the rudder. I have found that by reshaping those surfaces substantial gain in speed is secured without additional power, and the object of this invention is to disclose the improvements which have brought about those results.

Further and other objects and advantages 20 will be apparent from the specification and claims, and from the drawings which show by way of illustration what is now considered the preferred form of the invention.

Figure 1 shows a side view of a rudder and of a portion of a ship's hull to which my improvements have been applied.

Fig. 2 is a cross-section on line 2-2 of Fig. 1.

Fig. 3 is a cross-section on line 3-3 of Fig. 1.

Fig. 4 is a cross-section on line 4-4 of Fig. 1.

The hull of the ship is designated 10, the 35 propeller 12, and the rudder 14. To the rudder I rivet the rearwardly projecting plates 16 which are riveted together at their rear-most edges at 18 to form the V-shaped streamline cross-section shown in Fig. 2. In like manner plates 20 are secured to the sides of the stern frame above and in front of the propeller to produce the streamline cross-section as indicated in Fig. 3. The stern frame below 40 and in front of the propeller is streamlined by plates 22, as in Fig. 4. The stern frame to the rear of the upper part of the propeller is equipped with forwardly projecting plates 24 to provide a V-shaped cross-section similar 45 to Fig. 3. The forward edge 26 of the rudder, 50

in the rear of the propeller is streamlined in accordance with usual practice.

The improvements described above have been applied to several ships and in every case drag has been eliminated to such an extent 55 that increased speed has been obtained without increased power.

It is to be understood that the invention is not limited to the specific construction and embodiment herein described, but may be used 60 in other ways without departure from its spirit as defined by the following claims.

I claim:—

1. In a ship, a propeller, a stern frame having upright portions thereof positioned 65 only fore and aft of said propeller whereby the bottom of the frame is entirely open below said propeller, and means attached to said frame for stream-lining said portions towards said propeller, substantially as described.

2. In a ship, a propeller, a stern frame having upright portions thereof positioned only fore and aft of said propeller whereby 75 the bottom of the frame is entirely open below said propeller and means attached to said frame for providing said portions with V-shaped edges having the apices thereof projecting towards said propeller substantially as described.

3. The invention set forth in claim 2 in which said edges are formed of plates riveted to said frame portions and projecting therefrom.

4. In a ship, a stern frame having an open 85 bottom whereby the water has unimpeded access to the propeller, a rudder, and means attached to said frame and rudder for providing said frame and said rudder with V-shaped edges tapering toward the stern of 90 the ship, substantially as described.

5. The invention set forth in claim 4 in which said edges are formed of plates riveted to said frame portions and projecting therefrom.

6. In a ship, a propeller; a stern frame comprising an upper inverted U-shaped member having its vertical portions fore and aft of the propeller above the hub thereof, and a lower open-bottom member consisting 100

only of a single portion inclined downwardly and forwardly from a point adjacent said hub to the keel of said ship; and means for streamlining said frame members toward said propeller, substantially as described.

7. A stern frame for ships, comprising a downwardly open arch-shaped upper member having streamlined fore and aft members providing space for propeller blades, and 10 having a streamlined lower member arranged below and forward of the propeller to leave the frame open for unimpeded access of water to the propeller rotating on an axis located between said upper and lower members.

8. The invention set forth in claim 7 in which said lower frame member extends downwardly and forwardly from a point adjacent the propeller hub and away from the 20 line of rotation of the propeller blades.

9. In a ship, a propeller, a rudder, and a stern frame having a streamlined lower portion inclined downwardly and forwardly from the propeller hub, thereby permitting 25 unimpeded access of water to the propeller between said lower frame portion and said rudder.

10. In a ship, a propeller, a stern frame having an upper streamlined portion aft of 30 the upper part of the propeller and terminating above the propeller axis, and a rudder entirely supported by said upper frame portion and having the forward streamlined edge thereof located below said supporting streamlined frame portion.

11. A stern frame for ships, comprising a downwardly open arch-shaped upper member having streamlined fore and aft members providing space for propeller blades, and 40 having a streamlined lower member arranged to leave the frame open for unimpeded access of water to a propeller rotating on an axis located between said upper and lower members, in combination with a rudder entirely 45 supported by said upper frame portion and having a forward streamlined edge thereof located below said supporting frame portion, thereby providing streamlined frame and rudder edges fore and aft of said propeller, 50 with no part of said upper member below the propeller axis.

12. In a ship, a stern frame, and means for providing said frame with a rearwardly projecting V-shaped edge, said means comprising 55 plates riveted to said frame portions and projecting therefrom.

In testimony whereof I hereto affix my signature.

SAMUEL AITKEN.
